UNITED STATES PATENT OFFICE.

HENRY L. NEENNSTIEHL, OF WILMINGTON, DELAWARE, ASSIGNOR TO F. F. DALLEY COMPANY, INC., OF BUFFALO, NEW YORK, A CORPORATION OF NEW YORK.

BOX-OPENING DEVICE.

Application filed July 25, 1924. Serial No. 728,140.

To all whom it may concern:

Be it known that I, HENRY L. NEENNSTIEHL, a citizen of the United States, residing at Wilmington, in the county of New Castle and State of Delaware, have invented new and useful Improvements in Box-Opening Devices, of which the following is a specification.

This invention relates to a box opening device which is more particularly designed for use on a box having a body provided with a wall, having a lower external circumferential bead, and a cover provided with a flange fitting frictionally around said wall and having an upper external circumferential bead.

It is the object of this invention to provide an opening device for a box of this character which can be readily applied to such a box after the latter is manufactured, which does not require the formation of any openings in the box and thus prevents air from reaching the contents of the box and drying or deteriorating the same, which can be easily, effectively and conveniently manipulated for opening the box, which does not appreciably increase the space required for packing the same, and which can be manufactured and applied at low cost.

In the accompanying drawings:

Figure 1 is a front elevation of a box provided with my improved opening device.

Figures 2 and 3 are fragmentary vertical sections of the box, on an enlarged scale, through the front and rear parts of the box and opening device.

Figure 4 is a horizontal section taken on line 4—4, Figure 2.

Figure 5 is an edge view of the cam and its finger piece.

Figure 6 is a detached perspective view of the opening device.

Figure 7 is a fragmentary horizontal section of the rear part of the opening device.

Figure 8 is a top plan view of the box provided with the opening device.

Similar characters of reference indicate like parts throughout the several views.

The box adapted to be opened by my improved opening device consists of a body and a cover, each constructed of sheet metal. The body comprises a bottom 10, a circular wall 11 rising from the edge of the bottom and a lower external annular bead 12 arranged circumferentially on the wall below the up-

per edge thereof. The cover has a top 13, a depending circular flange 14 which fits frictionally around the wall of the body above the bead thereof, and an upper external annular bead 15 arranged circumferentially on 60 the flange above the lower edge thereof.

My improved opening device is constructed as follows:

The numeral 16 indicates a split ring or band constructed of a strip of sheet metal 65 which is bent so as to form two crescent shaped side sections 17 each of which is of channel form in cross section with the concave side facing inwardly, and a central front section the upper edge portion 18 of 70 which is turned horizontally inwardly to form a ledge or shoulder which is a continuation of the upper edge of the channel portions 17 while the lower part 19 of the same is arranged vertically and forms a vertical 75 guide lip or bracket which depends from the upper edge portion 18. One end of the split band is provided with an eye or opening 20 and the other end of the same is provided with a tongue 21 which is adapted to 80 be engaged with said eye and to be bent into a hook for interlocking the ends of the band.

On the central part of the lip 19 is pivotally mounted a prying member whereby upon turning the prying member the cover 85 may be loosened and pried off from the body for opening the box. For this purpose the central part of the lip 19 is provided with a vertical slot 9 and a prying member is provided which is constructed of a flat piece of 90 metal so as to form an elongated cam 22 which is normally arranged horizontally along the inner side of the lip, an elongated finger piece 23 normally arranged horizontally along the outer side of the lip, and a 95 narrow neck 24 arranged in said slot and connecting the central parts of the cam and finger piece.

The band is applied to the cover so that its channel shaped side sections fit over the upper bead on diametrically opposite sides thereof and the horizontal upper edge 18 of the central section rests on top of the upper bead, the lip 19 projects downwardly past the upper and lower beads, the tongue 21 105 is engaged with said eye and bent into hook form and the cam of the prying member is arranged below the upper bead. Upon placing the cover thus equipped with the opening device upon the body of the box the cam 110

will be turned into a horizontal position and lifted somewhat in the slot of the lip by engagement of the cam with the lower bead of the body.

- 5 When it is desired to open the body the prying member is turned in one direction or the other by the finger piece which causes the cam to bear at opposite ends against the upper and lower beads and separate the same 10 with a cam or lever action and thereby loosen the box members preparatory to completely separating them when access to the contents thereof is desired. During this prying action of the cam its neck floats or 15 moves vertically in the slot of the lip so that the cam is free to change its angular position without restraint which would not be the case if the neck of the cam were journaled at a definite point on the lip. The 20 slot in the lip also permits the lip and prying member to be readily assembled by passing the cam endwise through the slot of the lip before the band is secured to the cover, and after the band is mounted on the cover 25 the prying member cannot assume such a position as will permit the cam to slip outwardly through the slotted lip and dismember the same.

This opening device therefore, as a whole, 30 consists of two parts, which can be produced at low cost and capable of being readily and easily applied to a box of standard construction without requiring any alteration in the latter. The same is very compact and permits of packing the boxes in the same space 35 heretofore used for this purpose so that no increased expense or transportation difficulties would be experienced on this account.

Furthermore, this opening device avoids 40 the formation of any openings in the box through which air could enter the same and spoil the contents.

Moreover, this opening device permits of 45 applying a powerful prying action on the cover and body with comparative ease, thereby permitting of fitting the cover and body tightly on each other so as to effectually exclude air and preserve the contents of the 50 box indefinitely and still enable the box to be opened readily when required.

I claim as my invention:

1. A device for opening a box having a body provided with a wall having a lower

external circumferential bead, and a cover 55 provided with a flange fitting around said wall and having an upper external circumferential bead, said device comprising a band adapted to encircle said upper bead, and a cam pivotally mounted on said band and adapted to engage said lower bead. 60

2. A device for opening a box having a body provided with a wall having a lower external circumferential bead, and a cover 65 provided with a flange fitting around said wall and having an upper external circumferential bead, said device comprising a band having a part thereof constructed in the form of a channel which is adapted to receive 70 said upper bead and another part thereof forming a depending lip, and a cam pivotally mounted on said lip and adapted to engage said lower bead.

3. A device for opening a box having a body provided with a wall having a lower external circumferential bead, and a cover 75 provided with a flange fitting around said wall and having an upper external circumferential bead, said device comprising a band having a part thereof constructed in the form of a channel which is adapted to receive 80 said upper bead and another part thereof forming a depending lip having a vertical slot, and a rotatable member having an elongated cam arranged on the inner side of said lip and adapted to engage said 85 lower bead, an elongated finger piece arranged on the outer side of said lip, and a reduced neck extending through said slot and connecting the central parts of said cam and finger piece. 90

4. A device for opening a box having a body provided with a wall having a lower external circumferential bead, and a cover 95 provided with a flange fitting around said wall and having an upper external circumferential bead, said device comprising a band which is split at one point and is adapted to encircle said upper bead, one end of said band being provided with an eye and the other end of said band being provided with 100 a tongue adapted to engage said eye and bent into the form of a hook for locking said band on said upper bead, and a rotatable cam pivotally mounted on said band and adapted to engage said lower bead.

HENRY L. NENNSTIEHL.
